Primary Examiner — Thomas Johannes*Assistant Examiner* — Catherine Posthauer(74) *Attorney, Agent, or Firm* — Bond Schoeneck & King, PLLC; George McGuire(57) **CLAIM**

The ornamental design for a packaged automotive air freshener, as shown and described.

DESCRIPTION

FIG. 1 is a perspective view of a packaged automotive air freshener;

FIG. 2 is a front elevation view thereof;

FIG. 3 is a first side elevation view thereof;

FIG. 4 is a second side elevation view thereof;

FIG. 5 is a top plan view thereof;

FIG. 6 is a bottom plan view thereof; and,

FIG. 7 is a rear elevation view thereof.

The broken lines in FIGS. 1–6 are shown for the purpose of illustrating parts of the article that form no part of the claimed design. The broken lines of FIG. 7 represent perforations in the surface that form part of the claimed design.

1 Claim, 2 Drawing Sheets
